CHECK-CASH BOOK

Charles A. Frost, Brooklyn, N. Y., assignor to
 Du-All Check Book Company, Inc., a corpora-
 tion of New York

Application November 8, 1935, Serial No. 48,981
 Renewed March 5, 1938

2 Claims. (Cl. 281—29)

This invention relates to books which contain sheets to be written upon or filled in, such as blank books, check books and the like, and the invention resides in certain features of construction which form an improvement in the structure disclosed in the copending application Serial Number 32,544, filed by me and Ellsworth B. Dreher on July 22, 1935.

In said application, there is disclosed a combined check and cash book having sheets divided into three separable parts, an outer part forming a bank check or series of bank checks, an intermediate part having suitably designated spaces to be filled in as a cash book and an inner part forming the check stub.

In the closed position of the book, the checks are folded against the intermediate portions and sheets and the back cover of the book is provided with an extension to provide a backing 20 for the check while it is being filled out, this extension in the closed position being folded around the sheets onto the front cover.

The present invention as applied to the book above described comprises an improvement of 25 the construction of the hinged connection between the back cover and the extension, which permits the extension to be raised into contact with the uppermost or front checks, thus forming a firm backing for the check while it is being 30 filled out.

For this purpose I connect the extension with the back cover by a stiff strip having a width equal approximately to the thickness of the book, this strip being hinged along one edge to the 35 back cover and along its opposite edge to the stiff extension.

Various other objects and advantages of my invention will appear from the following description taken in connection with the accompanying 40 drawing, which shows one embodiment of the invention and wherein:

Figure 1 is a perspective view of the combined cash and check book in closed position;

Figure 2 is a perspective view of the book open 45 with one of the sheets unfolded and the cover extension raised into contact with the top check; and

Figure 3 is an end view of the back open showing the arrangement of parts when approximately 50 half of the checks have been removed, the top-most of the remaining checks unfolded, and the rear cover extension is raised into contact therewith.

The sheets 11 of the book 10 shown in Figure 55 2 are divided by perforations along lines a to

form check portions b and along lines c to permit the intermediate cash sheets d to be removed from the check stubs, there being large punchings or perforations g near the inner end of each of the sheets d to permit the sheets when removed to be mounted in a loose leaf binder. 5

The check portions of the sheets 11 are ruled as indicated in Figure 2 with suitable designations for the filling out of the check. The front side of the cash book sheets d are ruled with spaces r for information in regard to the corresponding check, the number of the check, date, the party in whose favor the check is drawn and, if desired, dates of invoices and accounts to which the same is chargeable. To the right of the spaces r are three columns l, m and n respectively. Column l is entitled "Amount of check" and columns m and n jointly entitled "Distribution". While titles of the individual columns m and n may vary with different businesses conducted by the drawers of the checks, convenient and generally applicable titles are "Accounts payable" or "Special accounts" for the column or columns m and "Other" for column n, this latter indicating a disbursement chargeable to 20 accounts other than "Accounts payable" or "Special accounts". 25

The front of the stub portions contain the number of the check and have spaces for the insertion of the amount of the check. 30

The back of the cash sheet as shown at the left of Figure 2 contains spaces for the insertion of bank deposits and information relative thereto. This side of the cash sheet is ruled with a date column o, a column p for the names of the 35 sources from which the deposits were received, a column q giving the deposit total brought forward and individual deposits and columns r' and s showing the distribution of deposits, the columns r' being "Special accounts" or "Accounts receivable" and the column s being marked "Other", and containing accounts other than the "Accounts receivable" or "Special accounts". 40

The back of the stub portion contains a column for the insertion of the balance brought 45 forward and the amounts of the individual deposits.

The amounts brought forward on the stub show the actual cash balance and this sum may be checked by subtracting the amount brought 50 forward on the check side of the cash sheet from the amount brought forward from the deposit side of the cash sheet.

Where more complete distribution of the items shown in columns n and s are desired, I 55

provide at the back of the book, a number of sheets which extend the length of the sheets 11. The former sheets are ruled on the left for credit distribution and on the right for debit distribution. I preferably provide a column between the credit and debit distribution columns for the items to be distributed. The distribution sheets are weakened along lines near the inner edge so that they can also be removed and are suitably punched for insertion in the loose leaf binder.

The check cash book when closed is approximately one third its length when opened. The check portions fold back upon the intermediate or inner portions of the leaves or sheets 11 and the back distribution sheets also fold at approximately the center.

One form of cover for the cash check book is shown at 14 in Figure 1. It comprises stiff front portions 15 and 16, the portion 16 being formed as a foldable extension of the back portion 17. The extension 16 is connected to the back portion 17 by a stiff strip 20 which is hinged along one edge at 21 to the back cover 17 and along the opposite edge at 22 to the extension 16.

The stiff connecting strip 20 permits the extension 16 to be raised into contact with the check to form a backing therefor while the check is being filled out. Figure 2 shows the extension with three of the first checks in the book unfolded and it will be seen that the strip 20 is substantially vertical. As more checks are used and torn out, the opening of the book at the uppermost of the remaining checks causes the plane of the outer folded edges of the sheets 11 to incline to the vertical. The width of this plane along which the strip 20 lies, is approximately the same width regardless of the number of checks left in the book as will be seen for example in Figure 3. The extension 16 may therefore be moved into facial contact with check regardless of the number of checks remaining in the book.

While I have described my invention as applied to a combined check and cash book, it is obvious that it may be applied to other books having folded sheets and it may be applied to either, or to both, front and back covers.

The portions 15 and 17 are preferably weakened along lines 48 adjacent the stub section so that when the check and cash portions are removed from the book all of the cover except the back binding may be removed, thus greatly

decreasing the space necessary for the storage of the stub portions.

Having now described my invention, what I claim and desire to secure by Letters Patent is:

1. A book comprising a cover and leaves folded each against itself and adapted to be unfolded to form respectively inner and outer portions and said leaves being weakened along lines of the folds whereby the outer portions may be successively removed from the inner portions and said outer portions being adapted for writing on one side thereof, a stiff strip hinged at one edge to one edge of the cover approximately in line with said folds and of a width approximately equal to the thickness of the book, an extension hinged to the opposite edge of the strip, the hinged connections between the strip and cover and extension being such that the strip may assume positions at acute angles to the cover and extension, whereby when said book is opened and a leaf unfolded, the strip may be swung to move the inner edge of the extension to the level of said last named leaf and the extension may be used for a backing for the outer portion of said last named leaf.

2. A book comprising a cover and leaves folded each against itself and adapted to be unfolded to form an outer part and intermediate part and a small inner part, the inner part having suitably designated spaces, on one side for filling out with the amount of the checks and on the other side for filling out with amounts of deposits, the intermediate having suitably designated spaces on one side for distribution of disbursements and on the other side for distribution of receipts, and the outer part having suitably designated spaces to be filled out as a bank check, the leaf being weakened along the fold which is between the check and intermediate parts, a stiff strip hinged at one edge to one edge of the cover approximately in line with said folds and of a width approximately equal to the thickness of the book, an extension hinged to the opposite edge of the strip, the hinged connections between the strip and cover and extension being such that the strip may assume positions at acute angles to the cover and extension, whereby when said book is opened and a leaf unfolded, the strip may be swung to move the inner edge of the extension to the level of said last named leaf and the extension may be used as a backing for the outer part of said last named sheet.

CHARLES A. FROST.
